CLAIM

The ornamental design for a comb, as shown and described.

DESCRIPTION

FIG. 1 is a top perspective view of a first embodiment of a comb showing my new design;

FIG. 2 is a front elevational view thereof, the rear elevational view being identical to the front view shown;

FIG. 3 is a right side elevational view thereof, the left side elevational view being identical to the right side view shown;

FIG. 4 is a top plan view thereof;

FIG. 5 is a bottom plan view thereof;

FIG. 6 is a top perspective view of a second modified embodiment, the undisclosed sides being identical to the first disclosed embodiment except for the absence of oval convexities; and,

FIG. 7 is a front elevational view of a third modified embodiment, the rear view being identical to the side shown. The undisclosed sides of FIG. 7 are identical to first embodiment except for the appearance of the pattern on the teeth.
